United States Patent Office

Des. 219,773
Patented Jan. 26, 1971

219,773

THEATER BUILDING

Pat R. Notaro, Malibu, Calif., assignor to Trans-Beacon Corporation, Beverly Hills, Calif., a corporation of Delaware

Filed Mar. 2, 1970, Ser. No. 21,690

Term of patent 14 years

Int. Cl. D25—04

U.S. Cl. D13—1

FIG. 1

FIG. 3.

FIG. 4.

FIG. 1 is a perspective view illustrating the front, top and right side of the building;

FIG. 2 is a top plan view of the building design;

FIG. 3 is a left side elevational view of the building design; and

FIG. 4 is a rear elevational view of the design.

I claim:

The ornamental design for a theater building, as shown.
